SPEAKER GRILL

Benjamin W. Lowell, Richmond Heights, Mo.
Application April 20, 1955, Serial No. 35,596

Term of patent 14 years

(Cl. D26—14)

The essential features of my design reside in the portions shown in full lines.

I claim:

The ornamental design for a speaker grill, substantially as shown and described.
